CLAIM

The ornamental design for a mobile power bank, as shown and described.

DESCRIPTION

This application also relates to U.S. patent application Ser. No. 14/589,494, filed Jan. 5, 2015, and entitled Uninterruptible Power Supply Having a Removable Battery, by George Hsia and Ming Che Chan.

FIG. 1 is an exploded perspective view of a mobile power bank showing our new design in environmental use; FIG. 2 is another perspective view of the mobile power bank;

FIG. 3 is a left side elevation view of the mobile power bank; FIG. 4 is a right side elevation view of the mobile power bank;

FIG. 5 is a front elevation view of the mobile power bank; FIG. 6 is a rear elevation view of the mobile power bank; FIG. 7 is a top plan view of the mobile power bank; and, FIG. 8 is a bottom plan view of the mobile power bank. The recessed channel of the mobile power bank shown with a symbolic break in length in FIGS. 1, 2, 7, and 8. The appearance of any portion of the article between the break lines forms no part of the claimed design.

(Continued)

The broken lines shown in the figures are for environmental purposes only and form no part of the claimed design.
